UNITED STATES PATENT OFFICE

154,497

DESIGN FOR A MEMORANDUM PAD HOLDER

Lyman S. Lanman, Oklahoma City, Okla.

Application March 13, 1948, Serial No. 145,079

Term of patent 3½ years

(Cl. D74—5)

To all whom it may concern:

Be it known that I, Lyman S. Lanman, a citizen of the United States, residing at Oklahoma City, in the county of Oklahoma and State of Oklahoma, have invented a new, original, and ornamental Design for a Memorandum Pad Holder, of which the following is a specification, reference being had to the accompanying drawing, forming part thereof.

The figure is a front perspective view of a memorandum pad holder, showing my new design.

I claim:

The ornamental design for a memorandum pad holder, as shown.

LYMAN S. LANMAN.
